UNITED STATES PATENT OFFICE.

JAMES DENARO, OF CAMBRIDGE, MASSACHUSETTS.

AUTOMATIC ICE-CREAM-CONE MACHINE.

Application filed October 26, 1915. Serial No. 58,020.

To all whom it may concern:

Be it known that I, JAMES DENARO, a citizen of the United States, residing at Cambridge, in the State of Massachusetts, have 5 invented a new and useful Automatic Ice-Cream-Cone Machine, of which the following is a specification.

My invention relates to improvements in machines for automatically molding and 10 baking pastry cones for ice cream receptacles, and it may be said to consist of improved mechanism for operating the molds and cores, and means of charging same, and delivering the cones trimmed and ready for 15 packing.

It is one of the objects of the present invention to greatly simplify the construction and operation of the machines of the character referred to, and to render such machines highly automatic in their operation 20 with an exceptional degree of reliability and efficiency. To obtain this end, I have provided improved means for opening the molds and raising the cores, in order to discharge the baked cones. I also have provided an improved baking oven construction, 25 parts of which serve the double function of slidably supporting the dividable female mold units. I have also obviated the possibility of the cores mutilating the finished 30 baked cones during the lifting of the cores in the discharging operation, and the possibility of scarring the mold sections when they are moved toward each other to establish 35 the baking position of the parts. Towards this end I have provided, as in the preferred embodiment shown, a parallel link suspension of the core carrying arm, and an operating device for this parallel link 40 suspension which is effective between the hub of the machine and the circle of the molding units. A distinct advantage arising from the use of such mechanism is in the slight, comparatively negligible, lateral 45 movement of the cores, particularly the apices of the cores during the early lifting movement. No substantial lateral movement of the cores takes place until after the cores have been lifted well clear of the 50 baked cones. The arrangement of the core carrier operating mechanism between the hub of the frame and the mold units renders it unnecessary to provide a movable filler spout for the batter, or to employ the

method of dipping the cores in a batter tank 55 to coat them as herein shown. If desired, a simple filler spout could be arranged across the path of the mold units and operated by suitable valve actuating mechanism to discharge batter into the closed 60 mold units at any desired position of the rotatable wheel. I have, however, in the embodiment of the invention herein shown, provided means for raising the cores above a dough-pan, then dipping them in 65 the dough and subsequently returning the cores to the mold suitably coated with batter.

I also obtain remarkably high production 70 of cones in a given time. This is due, among other things, to the arrangement of actuating means and devices to produce a simultaneous movement of the molding elements in their operation of opening to discharge the baked product. 75

By utilizing two spaced annular plates as main elements of the rotatable wheel or frame, I am able to cause them to serve as a part of the baking means, specifically, an oven, and also, in part at least, as a support 80 and slideway for the female mold elements. It is understood, of course, that the annular plates referred to are composed of parallel and straight sided sections arranged successively to take on a general arcuate character- 85

istic. Between the parallel walls of these sections the molding units are adapted to slide toward and from each other maintaining always a parallel relationship. 90 Other objects will be in part obvious and in part pointed out particularly hereinafter. The invention accordingly consists in the various features of construction, combinations of elements and arrangements of parts which will be exemplified by the construction hereinafter set forth and the scope of the application of which will be indicated 95 by the following claims.

Figure 1 is a plan showing a general arrangement of the machine. Figure 2 is a 100 view partly in section on line A—B in Figure 1. Figure 3 is a plan of a portion of the wheel. Figure 4 is a section on line C—D in Figure 1. Figure 5 is an elevation of the track for operating the core frame and 105 is taken on line E—F in Figure 2. Figure 6 is a detached view of the dough pump partly in section. Figure 7 is an end view

of the mechanism for operating the molds. Figure 8 is an enlarged view of the same showing the molds open. Figure 9 is a view showing the pipe connections for the gas burner, and Figure 10 an elevation of the cone trimming mechanism.

Similar figures refer to similar parts throughout the several views.

1, represents a vertical shaft free to turn 10 in a bearing 2 on a floor bracket 3, and resting on a thrust bearing 4.

Near the top of shaft 1 is a hub 5 supported by shoulder 6, and made to turn with the shaft 1 by set screw 7.

15 Threaded into the hub are the radial spokes 8 which hold the plates 9 and 10 in place with the assistance of the spacer 12 shoulder 11 and nut 13.

Bracing the spoke 8 and the plate 9 is the 20 rod 14 which extends to the hub 15 and is tightened by the nut 16. The hub is made to turn with the shaft 1 by set screw 17. 18, is a worm gear keyed to shaft 1. 19 is a worm meshing with worm gear 18 and 25 driven by the shaft 20 which turns in suitable bearings 21, 22, and 23, and derives its power from a motor 24 through suitable belting 25, and 26, and speed changing pulleys 27. 28 is a corner support bracket for 30 the frame 29 and braces 30 which are bolted to the hub 31 in which the end of shaft 1 revolves. On the brackets 28 is mounted a stud 32 supporting a roller 33 on which the plates 10 ride when the structure is revolved. 35 Each mold consists of two halves or sections 34 and 35, the ends of which slide in guides 36 and 37 on plates 9 and 10.

Mounted in a suitable bearing 38 in plate 10 and 39 in plate 9, is a cam shaft 40 carrying cams 41, acting against mould sections 34 and 35. 42 is a chain, one end of which is fastened to the mold frame 34, above the cam shaft 40, and the other end is passed around the roller 43 on cam 41, 45 and fastened to the mold frame 34 under the cam shaft 40. 47 is a segment of a pinion meshing with a rack 98 on bracket 100 which slides in guides 101 on plate 10. 99 is a roller on stud 102, projecting from 50 bracket 100. 103 is an unlocking cam track on frame 104 and 105 is a locking cam track on frame 104.

44 is a core frame carrying cores 45. On frame 44, are the spaced bearing pins 46 disposed in a vertical line and connected by parallel bars 47 to bearing pins 48 also disposed in a vertical line with the same spacing. Bearing pins 48 are mounted in a bracket 49 bolted to the hub 5. 50 is an up-right bar pivoted at 51 to bar 47 and at 52 to slide plate 53 which slides vertically in guides 54 on plate 9. 55 is a roller mounted on a stud 56 projecting from plate 53. The roller 55, engages a cam track 57, which 65 causes the cores to be raised out of the moulds

and high enough to pass over the leading edge, down into, then up and over the rear edge of the dough pan 58 which is secured to frame 59 by bars 60.

The dough is supplied to the dough pan 70 58 by a pump of which 61 is the cylinder; 62 is a piston; 63 a piston rod, and 64 another piston movable on rod 63. 65 is a spring acting to hold piston 64 against the adjusting nut 66, adjustably mounted upon 75 the threaded end 67 of rod 63. 68 is a spring to hold piston 62 out. 69 is a lever-arm acting on roller 70 which is mounted in the end of piston 62 on a pin 71, to force the piston in. 72 is a pin projecting from 80 plate 10 for engaging the lever 69 on the pump. The pump cylinder is securely fastened to plate 136 on bars 60. 73 is an inlet port and is connected to the dough supply tank 74 by a flexible hose 75. 76 is an outlet 85 port to dough pan 58. 77 are gas pipes with spaced holes to form burners for heating the oven above the moulds, which oven has for its sides plates 9 and 10, and top plate 78 which is suitably lined on the inside with 90 asbestos. The pipes 77 are secured to the top plate 78 with straps 79.

A portion of the top plate 80 is hinged at 81 and carries rails 82 which bear on the core frame 44, tending to press the core 95 frame very tightly on the mould frame. The desired pressure is obtained by springs 83 between the top of hinged plate 80 and frame brace 30. The oven below the moulds has gas pipe burners 84 supplied with gas 100 through pipes 85, 86, and 87, and controlled by valve 88. Pipes 89, 90, and 91 supply the upper oven. Air is forced into the pipe system by a blower 92 through pipe 93, the blower being driven by shaft 20 through 105 pulleys 94 and 95 and belt 96.

106 is a chute on which the cones drop when the moulds open, the cones sliding down this chute, and into the holes 107 in plate 108. The trimmer 109 is conical 110 shaped, with a greater angle than the pastry cone to impinge the edge of the hole 107 and trim the cone to the size of the hole. The cones drop through on to the conveyor 110 and are carried to the packing 115 table, while the trimmings slide down on the upper side of the plate 108 to conveyor 111 and are carried to a waste receptacle.

The trimmer 109 is mounted on shaft 112 which turns in bearing 113 on frame 114 and 120 is operated by arm 115 against which the projecting pin 116 on plate 9 acts to turn the trimmer into the holes 107, the trimmer being thrown back by the spring 117 which is fastened to frame 114 and to arm 118. 125 The chute 106 and plate 108 are suitably fastened to the frame 114.

The conveyor 110 is driven from the shaft 20 through pulley 119, belt 120, pulley 121, and shaft 122. The conveyor 111 is driven 130

from shaft 122 by pulley 123, belt 124, pulley 125, and shaft 126. 127 is a clutch sliding on key 128 in shaft 20, while 129 is a clutch-lever, and 130 a rod pivoted at 131 5 on the clutch lever, and at 132 on operating lever 133, which is pivoted at 134 on the frame 59.

The operation of this machine is as follows: The ovens and moulds being heated 10 to the proper temperature and the dough pan filled to the required depth, the motor started and the clutch thrown into engagement with the worm.

During the operation of the machine the 15 roller 55 rides up on the track 57 and is raised slightly as shown at G Figure 5. The roller 55, being connected to the core frame 44 through the stud 56, plate 53, the arm 50, the pin 51, bars 47, pins 46 and 48, 20 when the roller is raised to the level G, the cores are free from the cones, and at this point the moulds are timed to open and let the cones drop. As the wheel continues to revolve the roller 55 runs up to the level 25 H, which brings the cores high enough to pass over the edge of the dough pan 58, and from that level the roller drops to level I as indicated at I, which brings the cores into the dough to the required depth. The cores 30 being hot, sufficient dough adheres evenly to form a cone. When the roller is at the level J, the cores are over and above the edge of the dough pan, and so that they come down outside of the latter, and into the 35 moulds, and in this position pass into the oven, the dough pan being wide enough to allow of this operation without stopping the wheel. As the moulds enter the oven the core frame 44 slides under the track or 40 runner 82 which are attached to the hinged plate 80 and which in turn is held down by springs 83, and thus the cores are pressed down very firmly in the proper position in the moulds for a sufficient time to allow the 45 dough to become firm or hardened by the heat, after which the weight of the core frame and cores are all that is required to keep the cores in position.

It will be seen that the core frame is in 50 a horizontal position at all times, although swinging on the arc of the parallel bars 47, the advantage of this is that all the cores will be dipped in the dough to the same depth, and will always be in a vertical position in the moulds, even if some of the mould frames should be on different levels. 55 Also, they are maintained vertical while being moved into and out of the molds, so that the points of the cores do not engage the sides of the mold cavities. The cores are freed from the cooked cones by a movement that is substantially axial of the core and mold cavity, thus avoiding injury to the cones.

60 The moulds are caused to open by the ar-

angement of cam tracks shown in the detached view Figure 7. As the mould wheel revolves the roller 99 runs up on the track 103 and carries with it the bracket 100 on which are rack teeth 98 meshing with the 70 segments of pinions 97 keyed to the shafts 40 which turn in bearings 38 and 39 in the plates 9 and 10, and have cams 41 thereon for closing and holding the two half mould sections 34 and 35 together, and chains 42 75 and rollers 43 which act to separate the moulds as the bracket is raised by the track 103. The track is of sufficient length to hold the moulds open long enough to let the cones drop out, and when the roller 99 comes in 80 contact with the track 105 the bracket is forced down, turning the cams against the mould halves until the latter are tight together and the cams are on a dead center, thus holding the parts in that position with 85 the weight of the bracket also tending to hold them in position. When the cam shaft is turned in the opposite direction the rollers 43 on the end of the cam pull on the chain 90 90 and open the moulds.

The dough pump is gauged to supply the amount of dough taken out by each dipping of the cores, and is actuated by a projecting pin 72 on plate 10 coming in contact with lever 69 pivoted on plate 136, said lever acting against the roller 70 to force in the piston 62. The dough is fed into the pump through inlet 73 and tube 75 from tank 74, and fills the space between the piston 62 and piston 64, which space is maintained by the spring 65 on rod 63, and is adjusted by the nut 66 which has thread meshing with thread 67 on rod 63. The piston 64 being free to slide on the rod 63, when the piston is forced in, the amount of dough in the space between 100 the two pistons is carried to the outlet 76, and the piston 64 comes to a stop in the end of the cylinder just after passing the outlet 76, but the piston 62 continues to travel and compresses the spring 65 until the two pistons are together, thus forcing all the dough out of the space. The piston 62 is returned for another charge by the action of spring 68. The cylinder 61 is fastened to 105 the plate 136 by suitable straps 137.

The trimming mechanism is timed to operate just after the cones drop into the holes 107, in the plate 108, which latter is attached to the frame 114 at a right angle to the chutes 106, with the center of each hole 107 on a line with its chute, so that the cone will drop into it readily. The trimmer being up out of the way when the cone drops, swings down when the pin on plate 9 comes in contact with arm 115, centers the cone, and trims the edges.

The forms of construction which have been particularly illustrated and described admit of minor changes and modifications, therefore the right is reserved to such changes and 130

modifications that do not depart from the spirit and scope of the invention which is defined in the appended claims:

1. In a machine of the class described, a wheel structure consisting of a vertical shaft driven continuously by a motor through suitable gearing, a hub on said shaft with radial spokes in combination with an outer vertical plate, an inner vertical plate, said outer and inner plates forming the sides of a circular oven the said inner plate held against a shoulder on said radial spoke, and said outer plate held against a spacer on said radial spoke between said inner plate and said outer plate by a nut on said radial spoke bearing against the outside of said outer plate, said radial spokes being on the radial joining line between one set of inner and outer plates and the adjoining set of inner and outer plates, horizontal guides on said plates on which slide two half mould sections in the space between the inner plate and the outer plate, and at a tangent to a line from the center of said hub through the center of the space between said radial spokes, a cam shaft on each side of said half mould section with a cam acting to force said half mould sections together to form a complete mould section, and a roller on said cam acting on a chain both ends of which are fastened to the said half mould section, with the loop over the said cam shaft to separate said mould sections, and means for turning said cam shaft to open and close said mould sections at a certain point in the revolution of the wheel structure.
2. In a machine of the class described, a movable carrier having mounted thereon a moulding device, consisting of two half mould sections sliding on horizontal guides to allow of said mould sections being moved to join or separate with a parallel motion of said mould sections, a shaft mounted in bearings parallel with each of said mould sections, cams on said shafts acting to force said half mould sections together to form a complete mould section, rollers on said cams, a chain looped over each of said rollers, with one end fastened to said mould section above said shaft, and the other end fastened to said mould section below the said shaft and acting to separate the said mould sections, a pinion on each of said shafts, a bracket with racks meshing with said pinions, vertical guides for said bracket, a projecting roller on said bracket engaging a cam track to lower and raise said bracket, substantially as described, and for the purpose set forth.
3. In a machine of the class described, a rotatable wheel structure embodying a circular oven in combination with a circular plate forming the top of said oven, said circular plate having a portion cut away, to allow for charging and discharging the said oven, a free end portion of said circular plate being hinged at the point where the charged moulds enter the oven, molds adapted to enter said ovens, a frame carrying cores co-operating with said molds, cam rails attached to the under side of said hinged portion, said rails bearing on the frame carrying cores for said mould, springs pressing on said hinged portion between the upper side of said hinged portion and a top frame brace, substantially as described, and for the purpose set forth.
4. In a machine of the class described, a plurality of mold sections, a plurality of core sections each co-operating with a mold section and movable in axial alignment therewith, a movable carrier on which said mold sections and core sections are mounted, a dough pan in vertical axial alignment with said mold and core sections during the charging period, means for rotating said mold and core sections, means for immersing said core sections in said dough pan and subsequently inserting them in said molds.
5. In a machine of the class described, molding devices including a pair of two part mold sections having a plurality of mold faces and a core for each mounted upon a core carrier, a movable carrier on which said molding devices are mounted, means for opening and closing said mold sections to discharge the finished product therefrom, means to operate the core carrier to raise and lower the cores relative to the molds and means for applying a coating of batter to the cores while they are raised from the molds.
6. In a machine of the class described, molding devices including a pair of two part mold sections having a plurality of mold cavities and a core for each mounted upon a core carrier, a movable carrier on which said molding devices are mounted, means for opening and closing said mold sections to discharge the finished product therefrom, means to operate the core carrier to move the cores axially of the molds and means for applying a coating of batter to said cores while aligned vertically with said molds.
7. In a machine of the class described, a rotatable mold section, a core section therefor in axial alignment therewith, a dough pan in vertical axial alignment with said mold and core sections during the period of coating the core with batter, means for imparting relative movement between said core section and said dough pan, means for discharging formed cones from said mold section and a rotatable carrier on which said mold and core sections are mounted.
8. In a machine of the class described, a rotatable mold section, a core section therefor in axial alignment therewith, a dough pan in vertical axial alignment with said mold and core sections during the period of

coating the core with batter, means for imparting relative movement between said core section and said dough pan to immerse the former in the batter in said dough pan
 5 to coat the core therewith, means for releasing formed cones from said mold sections, means adjacent with said mold sections to receive said cones and trim therefrom surplus material and a rotatable carrier on which said mold and core sections are mounted.

9. In a machine of the class described, a rotating mold section, a core section co-operating therewith and in axial alignment thereto, a dough pan in axial alignment with said mold and core sections at times, mechanism adapted to impart relative movement of said core section to said mold section and in axial alignment therewith and 20 at times to immerse the core section in said dough pan and a rotatable carrier on which said mold and core sections are mounted.

10. In a machine of the class described, a rotating mold section, a core section co-operating therewith in axial alignment thereto, a dough pan in vertical axial alignment with said mold and core sections during the period of coating the core with batter, mechanism adapted to impart relative movement 30 of said core section to said mold section in axial alignment therewith and to immerse the core section in said dough pan when vertically thereover, means for discharging the formed cone from said mold section and a rotatable carrier on which said mold and core sections are mounted.

11. In a machine of the class described, a rotating mold section, a core section co-operating therewith in axial alignment thereto, a dough pan in vertical axial alignment with said mold and core sections during the period of coating the core with batter, mechanism adapted to impart relative movement of said core sections to said 45 mold section in substantially axial alignment therewith and to immerse the core section in said dough pan, means for discharging formed cones from said mold section, a rotatable carrier on which said mold and core sections are mounted and trimming means in circumferential alignment with said mold sections and adapted to receive the discharged cones and trim therefrom all surplus material.

12. In a machine of the class described, comprising a plurality of mold sections, core sections for each of said mold sections and movable in substantially vertical alignment therewith, a rotatable carrier on which said 60 mold and core sections are mounted, mechanisms for imparting relatively vertical movement between the said mold sections and core sections, a dough pan within the path of rotation of and in vertical alignment 65 with said core and mold sections, means for

imparting relative movement between said dough pan and said core sections to immerse the latter within the former to coat the core sections with batter and return the same to the mold sections.

13. In a machine of the class described, a plurality of two part mold sections and core sections therefor, a carrier for said sections rotating within a horizontal plane, a dough pan in vertical axial alignment thereto within the plane of rotation of the mold sections and the core sections, mechanism adapted to impart movement of the said core section relative to the mold sections and to impart relative movement between the core sections and the said dough pan, and means for separating said two part mold sections to permit the molded cone to discharge therefrom.

14. In a machine of the class described, a plurality of two part mold sections and core sections therefor, a carrier for said sections rotating within a horizontal plane, a dough pan in vertical axial alignment thereto, mechanism adapted to impart relative movement between the core sections and said dough pan, means for separating said two part mold sections to permit the molded cone to discharge therefrom, and trimming means to trim surplus material from finished cones.

15. In a pastry baking machine, a horizontally rotatable wheel carrying a plurality of divided female molds and a plurality of male cores, cooperating respectively with the female molds, and means for effecting a separation of the female molds and a lifting of the male cores substantially simultaneously; said means comprising a parallel link mechanism associated with the male cores and a means for effecting a separation in parallelism of the divided female molds.

16. In a pastry baking machine, a horizontally rotatable wheel carrying a plurality of sets of divided molds and cooperative core members, and a plurality of radially extending links pivoted to the hub of the said rotatable wheel and grouped in parallel pairs, each group comprising upper and lower spaced links and each group being attached to the core member of each set.

17. In a pastry baking machine, a horizontally rotatable wheel carrying a plurality of sets of divided molds and cooperative core members, a plurality of radially extending links pivoted to the hub of the said rotatable wheel and grouped in parallel pairs, each pair comprising upper and lower spaced links and each group being attached to the core member of each set, and means intermediate the hub of the wheel and the core members for governing the movement of the parallel links.

18. In a pastry baking machine, a hori-

zontally rotatable wheel having slidably mounted thereon, between vertical, inner and outer walls, a plurality of molds provided with molding cavities, a plurality of core members, the cores of which are adapted to cooperate with the molding cavities, and a fixed top plate enclosing the said molds and core members during the major part of their travel; the said top plate cooperating with the said vertical, inner and outer walls enclosing the molds to form there-with a main baking chamber.

19. In a pastry baking machine, a horizontally rotatable wheel having mounted thereon, between vertical, inner and outer walls, a plurality of female mold units each composed of two half mold sections, the said vertical, inner and outer walls being adapted to serve as slideways for the said mold sections.

20. In a pastry baking machine, a horizontally rotatable structure comprising a hub with radially extending means supporting inner and outer spaced vertical walls, and a plurality of molding sets supported by said structure, each set comprising a pair of half mold sections and a core; the mold sections being arranged to open and close by sliding in guideways formed in the spaced walls.

21. In a pastry baking machine, a horizontally rotatable structure comprising a hub with radially extending means supporting inner and outer spaced vertical walls, a plurality of molding sets supported by said structure, each set comprising a pair of half mold sections and a core; the mold sections being arranged to open and close by sliding in guideways formed in the spaced walls, and the core being connected to the hub by means of a parallel link mechanism.

22. In a pastry baking machine, a hori-

zontally rotatable structure comprising a hub with radially extending means supporting inner and outer spaced vertical walls, a plurality of molding sets supported by said structure, each set comprising a pair of half mold sections and a core; the mold sections being arranged to open and close by sliding in guideways formed in the spaced walls, and a stationary top cover plate under which the said structure rotates to form with the vertical walls a main baking chamber for the molding sets.

23. In a pastry baking machine, a horizontally rotatable structure comprising a hub with radially extending means supporting inner and outer spaced vertical walls, a plurality of molding sets supported by said structure, each set comprising a pair of half mold sections and a core; the mold sections being arranged to open and close by sliding in guideways formed in the spaced walls, the core being connected to the hub by means of a parallel link mechanism, and a stationary top cover plate under which the said structure rotates to form with the vertical walls a main baking chamber for the molding sets.

24. In a pastry baking machine, a female mold unit comprising two half mold sections located between vertical, spaced plates and slidably mounted in horizontal guideways therein, whereby the said mold sections are permitted to move in order to join or separate, and means located between the said vertical, spaced plates adapted to hold said mold sections in closed position whereby tendency of the mold sections to separate under pressure of generated steam or gas is positively resisted.

JAMES DENARO.
